PLUG HANDLE

Marie J. Best, Yonkers, N. Y.

Application December 31, 1941, Serial No. 425,053

3 Claims. (Cl. 4-295)

My invention relates to a handle for drain plugs and stoppers and particularly the stopper of wash basins, sinks, tubs, etc. Among the purposes and objects are to provide:

A handle and plug which may be easily removed even when the user's hands are soapy and slippery and to clean the drain pipe.

A handle for plugs made of rubber and the like and having no metal parts.

A handle which will not easily become accidentally removed and suitable to operate the plunger extension.

A drain plug handle at the edge or eccentric from the center of the plug.

A simple convenient plug for general use.

I accomplish these and other objects by the construction herein described and shown in the accompanying drawing forming a part, in which:

Fig. 1 is a perspective view showing the application of my device.

Fig. 2 is a plan view.

Fig. 3 is an enlarged section and elevation showing my device in place.

Fig. 4 is a front elevation.

Fig. 5 is a front elevation of a modification.

Fig. 6 is a side elevation.

Fig. 7 is a side elevation and partial section at the center line of the modification shown in Fig. 5.

Similar reference characters refer to similar parts throughout the several views of the drawing and in the specification to follow.

The ordinary rubber drain plug with its metal ring and chain is so well known, that I am pointing out the troublesome features only, for the purpose of comparison. The ordinary plug becomes soft and the ring tears through the softened eye.

The handle on my plug is at one side and large enough to easily lift the plug from its water tight tapered seat because it lifts one edge first and does not lift the plug from the center, thus starting the entire joint loose at one pull as is the case with the ordinary plug.

The pull is made on the chain of the ordinary plug; the chain and also the plug become slippery due to the soapy water used, making it difficult to pull the plug. The handle on my plug has a square edged shoulder which helps the user to grip the plug.

My plug preferably is formed of a minimum of rubber or other springy material and thus saves metal needed for war purposes.

The plunger extension on my plug automatically cleans the drain pipe by the withdrawal

of the plug from its seat and the withdrawal and movement of the plunger in relation to the small end of the seat of the drain fitting.

In the following specification and in the drawing, I have not attempted to show all of the possible modifications of my device, but rather to illustrate and describe in detail my preferred construction so that it may be better understood by those skilled in the art to which this invention pertains. It is believed that after a study of this disclosure, numerous modifications may be apparent which do not depart from the underlying principles of which this detailed disclosure is an embodiment.

15 Referring to the drawing, the lower part 1 of my plug is preferably slightly larger in diameter at or near the top surface 2 than the top of the seat 3 of the drain fitting 4 which is of the conventional type used in wash basins, bath tubs, sinks, etc., in which the seat 3 is a tapered bore or opening 5 directly connecting the drain pipe 3' with reservoir 4' of water to be drained. The bottom edge 6 is of similar diameter to the small diameter of the tapered bore of the seat in the fitting 4.

10 The periphery 7 of the lower part 1 of my plug is not tapered to suit the taper of the seat but is preferably a spherical surface 8, the center of which is at 9, thus between the ends of the tapered bore 5 contact is made with the spherical surface 8 of my plug, when in place, thereby closing the drain, yet, when the plug is moved or tilted by the handle 10, the tendency of the plug to stick in its seat is overcome so that it may be easily removed.

15 The handle 10, of my plug, is preferably disposed eccentric to the center 9, between said center and periphery 7 where the neck 11 of the handle joins the top surface 2. The axial centerline 12 of the handle is preferably disposed at an angle 5' to the axial centerline 13 of the lower part 1 of my plug.

20 The eccentric and also the angular disposition of the handle in relation to the bottom end of the plug, together with its spherical surface, facilitates its easy removal.

25 The finger aperture 14 of the handle is provided with relatively sharp edges 15 and the shoulder 16 above the neck 11 is likewise provided with the sharp edges 17, all of which prevent the fingers of the user from slipping when tilting and pulling the plug in relation to its seat.

30 The lower part 1 is preferably extended below and beyond the bottom edge 6 into the cylindri-

cal plunger 18, which, together with the part 1, is preferably of greater length than the diameter of the periphery 7. The plunger 18 has a diameter, throughout its cylindrical length, equal to the small diameter of the tapered bore 5 of the fitting 4 which thus forms a substantially pressure tight joint around the plunger, thereby causing a partial vacuum to be formed in the drain pipe by the upward movement of the plunger and plug.

The upward and downward movement of the plunger causes an upward and downward surge in the drain pipe to dislodge lint, threads, hair, etc., automatically cleaning the drain pipe.

The plunger portion is preferably of relative soft rubber or similar material having sufficient resiliency to cause the plunger to yieldingly fit the small part of the bore.

In the modification shown in Figs. 5 and 7, the axis 12' of the handle 10' is disposed parallel to the centerline 13' of the lower part 1'. The finger depression 14' is provided with sharp edges as is the shoulder 16'. The other parts are similar to the parts shown in the other views and the reference characters are designated by a similar number with the added prime characteristic (') and the description of the preferred construction above applies to the modification shown in Figs. 5 and 7.

Having thus described my device in detail, my invention is set forth in the appended claims.

I claim:

1. In a drain plug suited to fit and plug the

drain fitting of basins, tubs, and other reservoirs, a lower portion adapted to engage the seat of said fitting, handle means having relatively sharp non-slipping edges formed above the top surface of said lower portion and said lower portion having a periphery substantially conforming to a part of the surface of a sphere, said handle means being disposed eccentrically to center of said lower portion.

2. In a drain plug suited to fit and plug the drain fitting of basins, tubs, and other reservoirs, a lower portion adapted to engage the seat of said fitting, handle means secured to the top of said lower portion, said lower portion having a periphery curved between its top and lower edges and a cylindrical downwardly disposed plunger below said lower portion slidable in said fitting to cause an up-movement of the liquid in said drain pipe by the movement of said drain plug.
3. In a drain plug for basins, tubs, and the like, having a tapered plug seat, an integral plug engaging said seat, and a handle above said plug, and an integral depending cylindrical plunger below said plug slidably and snugly fitting the small diameter of said tapered seat and movable up and down by said handle, thereby to cause a surge of the liquid in the drain, said cylindrical plunger having a yielding body such as rubber or the like, to form an air and water tight joint between said seat and said plunger while being moved up and down.

MARIE J. BEST.
